UNITED STATES PATENT OFFICE.

J. CHARLES APPLEBY, OF JERSEY CITY, NEW JERSEY.

APPARATUS FOR COVERING WIRE WITH SOFT METAL.

SPECIFICATION forming part of Letters Patent No. 374,166, dated December 6, 1887.

Application filed April 26, 1887. Serial No. 236,159. (No model.)

To all whom it may concern:

Be it known that I, J. CHARLES APPLEBY, a citizen of the United States, residing at Jersey City, in the county of Hudson and State of New Jersey, have invented certain new and useful Improvements in Means for Covering Wire Cables, Wire, &c., with Lead, Alloy, Soft Metal, or other Plastic Material; and I do hereby declare that the following is a full, clear, and exact description of the invention, which will enable others skilled in the art to which it appertains to make and use the same.

This invention is more particularly intended for covering wire cables, comparatively stiff wire, &c., with lead, alloy, soft metal, or other plastic material, with the object of avoiding the necessity of giving sharp bends or curves to the cable or wire, as the case may be. Said invention may, however, be employed for covering cables or wire of more flexible character, if desired. It may, further, not only be used for covering such articles with lead, alloy, or other soft metal, but also for covering metallic cables, wire, &c., with any suitable plastic material, either for the purpose of electrically insulating the same or for the purpose of protecting the same from external injury.

One feature of my said invention is, furthermore, also intended to permit one and the same set or system of covering devices to be employed upon cylinders varying in diameter, thereby enabling one of such set or systems to be employed, as occasion may require, upon one or another of several cylinders of differing capacities.

My invention comprises certain novel combinations of parts, whereby the objects aforesaid are effectually secured.

Figure 1 is a vertical transverse sectional view taken in the line xx of Fig. 2, representing an apparatus embracing my said invention. Fig. 2 is a side view and partial sectional view taken in a plane at right angles to Fig. 1 of said apparatus. Fig. 3 is a plan view of the same.

At A and B are represented, respectively, the upper part of the cylinder, in which is placed the material with which the cable or wire is to be covered, and the piston or plunger, actuated by hydraulic or other suitable power, by which said material is ejected from

the cylinder in the operation of covering the cable or wire, as the case may be.

C is the head, to which is provided, as hereinafter explained, the devices by which the covering material is placed upon and around the cable or wire. This head C is firmly secured upon the end of the cylinder A by any suitable means—as, for example, by transverse bolts a , passing through coincident holes in lugs b on the head C, and lugs c , secured to the side of the cylinder A. Any other preferred means of securing the head C to the end of the cylinder may be employed.

Upon the inner end or surface of the head C are provided annular ribs or splines e , which may be two or more in number, and which, when the head is in position upon the cylinder, should be concentric with the longitudinal axis of said cylinder. When the head C is in its place upon the end of the cylinder, one or more of these ribs or splines e fit into corresponding grooves f , formed in the contiguous end of the cylinder and concentric with the axis of the latter.

By providing several cylinders of different diameters, but each with a system of grooves, f , which have the same radius and a similar cross-section with the corresponding ribs of the head C, the head C may be used at will upon any of said cylinders. With a cylinder of smaller diameter the innermost of the ribs e will be within the line of the internal walls of the cylinder; but the outermost of such ribs will fit into the grooves of the corresponding radii in such cylinder, so that within certain predetermined limits one cylinder-head C may be used with several cylinders.

The head C has at one side an inlet-passage, g , and at the opposite side, preferably higher than the inlet-passage g , is an outlet-passage, k . This outlet-passage k may be placed lower down or higher up, so long as its relation with the inlet-passage g is such that the cable or wire (indicated at D) is not bent to a degree sufficient to bring the cable or wire entering and leaving through said passages to a right or acute angle, it being the object of the feature of the invention now under consideration to enable the cable or wire to be covered without bending the same to any considerable degree. Interposed between the inlet-passage g

and the outlet-passage *k* is an annular die, *E*, which is preferably externally threaded, so that it may be held in place by being screwed into a fixed nut, *m*, suitably provided in the head *C*. A tubular core, *F*, is in like manner inserted between the inlet-passage *g* and the outlet-passage *k*, and behind the annular die *E*. The space *n*, between the apex of the tubular core *F* and the annular die *E*, determines the thickness of the covering placed upon and around the cable or wire *D* in the operation of the apparatus, and a space, *r*, around the tapering or conical portion of the tubular core *F*, behind the annular die *E*, communicates 15 by passages *G'* with the interior of the cylinder *A*, said passages joining the space *r* at opposite sides of the tubular core *F*, so that when the lead or other soft metal or plastic material in said cylinder is forced outward by 20 the piston or plunger *B* it passes through the passages *G'* into the annular space or chamber *r*, and thence between the apex of the tubular core *F* and the annular die *E*, and around and upon the cable or wire *D* simultaneous with 25 such passage of said cable or wire. Said cable or wire, as the case may be, is covered by or inclosed within the plastic material, which, in effect, forms a pipe or tube around the same. In order that the cable or wire *D* may pass 30 readily to and through the tubular core *F* and annular die *E*, the head *C* is chambered adjacent to the inlet-passage *g* to provide room for a pulley or roller, *I*, the circumference of which is preferably grooved, and which is arranged 35 in such relation to the inlet-passage *g* as to guide the cable or wire *D* while the same is passing through the inlet-passage *g* into direct and due relation with the tubular core *F*, thereby insuring the proper transmission of 40 the cable or wire *D* through the tubular core and the annular die, and also preventing any undue friction upon the cable or wire as the same is guided to the tubular core and the annular die, as explained. 45 By means of my invention, therefore, I am enabled to cover cables, comparatively stiff wire, and the like without subjecting the same to short bending, which in some cases is almost impracticable, and in others—as, for example, in covering with lead or other soft metal wires already provided with a covering of gutta-percha or other insulating material—is liable to injure such covering or insulating material. I am also enabled to effectually cover such relatively stiff wire or 55 rigid cables or wires without undue friction upon their surfaces or upon the insulating-covering with which they may be already protected. Furthermore, as the annular die *E* and tubular core *F* may be readily replaced by others of different internal diameters or proportions, and inasmuch as the head *C* may, as hereinbefore explained, be used upon cylinders of different capacities or provided with

pistons worked with different power, I am enabled by the use of one and the same head *C* to employ cylinders of different capacities, power, &c., as occasion may require, in the production of covered cables, wires, &c., of different diameters, different thicknesses of 65 covering, &c. I am, furthermore, enabled to adjust one and the same head upon such cylinder, as the exigencies of the case may require. Any suitable means may be employed for maintaining the contents of the cylinder 70 A at the temperature best calculated to secure the required degree of plasticity, and in like manner any suitable means may be employed to prevent the head *C* and the parts carried thereby from becoming overheated. 75 The die *E*, instead of being of a true annular form to cover cylindrical wires, cables, &c., may be of any other suitable shape to conform to that of the cable, wire, or other article to be covered. Thus, for example, for 80 a cable more or less flattened the die would be of elongated shape, the general contour of the die corresponding to that of the cross-section of the cable, wire, or other article to be covered. It is therefore to be understood 85 that the term "annular," as employed in this specification and the claims thereof, is sufficiently comprehensive to include dies circular, oblong, cruciform, rectangular, or other in their contour. 90

What I claim as my invention is—

1. A head for the cylinders of wire-covering machines provided with an annular die, *E*, a tubular core, *F*, and suitable passages for the transmission of the cable or wire to be covered and for the inflow of the covering material to the die, and constructed with a plurality of annular ribs *e*, all substantially as and for the purpose herein set forth. 95
2. In an apparatus for covering wire, the combination of a cylinder having substantially a plain face at its open end, a head provided with a passage and connected with the opening of the cylinder, and with a covering-forming die within the head, and a rib or ribs surrounding the opening of the cylinder and serving to prevent the lateral escape of the covering material, and mechanism for fastening said covering-head upon the end of the cylinder, substantially as described. 105
3. The combination, in a wire-covering machine, of a removable head, *C*, containing passages for the wire to enter and leave said head, the core *F*, surrounding the wire, the die *E*, serving to determine the size of the covering of the wire, the passage *G'*, and the rib or ribs *e* for making a joint between the cylinder *A* and head *C*, substantially as described. 115
